ENGINE STAND

Louis Clergy, Des Moines, Iowa; Henry Clergy
administrator of Louis Clergy, deceased

Application November 23, 1936, Serial No. 112,319

2 Claims. (Cl. 29—89)

This invention relates to improvements in stands adapted to support a machine or device being repaired, such as an airplane engine, after the engine has been removed from the plane.

5 The object of my invention is to provide a simple, durable and rigid stand to which an airplane engine or the like may be rigidly secured, and when so secured, may be easily and quickly moved from one position to another and rotated about two axes so that the operator may have accessibility to any part of the engine needing repair, without having to reset the engine on its stand, and furthermore to provide means whereby the engine may be easily and quickly adjusted 10 to any desired position, and at the same time rigidly support the engine against accidentally falling to the floor.

A further object of my invention is to provide, in a stand of the type above described, improved means for mounting an engine whereby it may be tilted about a horizontal axis, and in connection therewith improved means for tilting said mounting means and at the same time provide means whereby it may be easily and quickly 15 locked in the desired tilted positions.

A further object is to provide, in a stand of the type above described, improved means for portably supporting the stand where it may be easily moved from one position to another over the floor, and in connection therewith means for locking the stand against movement, when so desired.

30 My invention consists in the construction, arrangement and combination of the various parts of the device, whereby the objects contemplated are attained, as hereinafter more fully set forth, pointed out in my claims, and illustrated in the accompanying drawing, in which:

Figure 1 is a side elevation of my improved stand.

40 Figure 2 is a plan view of the same.

Figure 3 is an end elevation.

Figure 4 is a detail sectional view taken on the line 4—4 of Figure 3, a portion of one end of the supporting base being broken away.

45 Figure 5 is a detail sectional view taken on the line 5—5 of Figure 2.

Figure 6 is an enlarged detail sectional view taken on the line 6—6 of Figure 2.

50 My improved stand comprises a supporting frame 10 formed of a pair of parallel angle irons 11, connected by means of cross rods 12. Secured to the central portion of each member 11 is an upright angle iron 13, having its upper end connected to the upper end of a brace 14, the

lower end of said brace being connected to the outer end of one of the bars 12. The members 13 are connected by cross brace members 15, thus providing means whereby the upper ends of the members 13 are rigidly supported to the members 11 and spaced apart to receive between them what I shall term the table 16. The table 16 is secured to the members 13 by means of pivots 17, said pivots being located between the ends of the members 16 so that the table is 10 partially balanced and free to swing from the horizontal position shown in Figure 1, to an inclined position as illustrated in Figure 4.

The table comprises a pair of parallel angle bars 18 having their free ends connected to cross bars 19, the bars 19 being supported on top of the ends of the members 16. The long or front end of the table 16 is pivotally connected to the upper ends of a pair of rack bars 20, the lower ends of said rack bars being slidably and 20 telescopically mounted in tubular brace members 21 pivotally mounted on the front bar 12.

Fixed to the inner side of the upper end of each of the members 21 is a bracket 22 for supporting a shaft 23, said shaft carrying pinions 24 adapted to mesh with the teeth of the rack bar 20 in a manner as clearly illustrated in Figure 4, the teeth of the pinion 24 entering the tube 21 through a notch 25. By this arrangement it will be seen that if the shaft 23 is rotated, then the rack bar 20 will move into or out of the tubular member 21, causing the table 16 to be tilted. The bars 20 may be locked in any desired adjusted position by means of a hand actuated screw 26 mounted in a suitable bearing 27 carried by the upper ends of the members 21 and adapted to engage the outer surface of the bar 20.

40 For rotating the shaft 23 I have provided on one end of the said shaft a gear 28 adapted to mesh with a pinion gear 29 carried by a stub shaft 30, said stub shaft 30 being rotatably supported in a bearing 31 carried by one of the members 21, as illustrated in Figure 3, the outer end of the shaft 30 being provided with a crank 32 by means of which the pinion 29 may be rotated and, in turn, the gear 28, causing the shaft 23 to be rotated. A gear housing 33 is supported by the shafts 23 and 30.

50 Supported on the members 18 and the table 16 I have provided four upwardly extending shafts 34, each of which is provided with a grooved roller 35, said rollers being so arranged as that an annular support 36 may be carried in the grooves of said rollers and free to rotate 55

about an axis perpendicular to the table 16. This support 36 is provided with nine holes 37 for receiving bolts by means of which the engine base may be fixed to said annular member 36. In this connection it might be noted that airplane engineers have adopted a standard base for all airplane engines having nine holes for receiving bolts for securing the engine to the support, the holes 37 being mounted and spaced to meet the standard requirements.

The bottom of the annular member 36 rests on the cross members 19 so that the said members 19 serve to support a portion of the weight of the engine when the table is in a horizontal position, and when the table is in a vertical position the weight is carried by the lower rollers 35. By this arrangement it will be seen that if the table is in a horizontal position, then the engine may be rotated about a vertical axis. If a commercial type of airplane engine is supported thereon, in which the cylinders are usually mounted in radial manner, then the cylinders will be supported in a common horizontal plane. It will readily be seen that any of the cylinders may be brought to position in front of the operator standing at one side of the frame, by simply rotating the support 36. Or, if so desired, the table 16 may be tilted and the engine rotated about a horizontal axis.

For locking the member 36 against rotation I have provided in one of the members 19 a threaded shaft 38 mounted in an opening 39 formed in the member 19, having its upper end provided with a head 40, the periphery of said head having a notch 41 for receiving one edge of the member 36. A screw-threaded sleeve 42 is carried by the lower end of the shaft 38, having a hand wheel 43 by means of which the sleeve may be easily rotated to force the flange 44 of the head 40 against the member 36, in turn forcing the member 36 against the member 19.

In order that the stand may be easily moved from one position to another I have mounted one end of the stand on rollers 45, carried by brackets 46 fixed to the members 11. The opposite ends of the members 11 are carried by swiveled casters 47 so that the stand may be easily steered when so desired. However, sometimes it is desired to fix the stand against free movement. To accomplish this I have provided in each of the horizontal flanges of the members 11, downwardly extending brackets 48, having their upper ends screw-threaded and extended through openings 49 in said members 11, the upper ends being provided with a lock nut 50 for securing the member 48 in position. The member 48 is provided with a recess 51 and a hole 52 in its lower end. A shaft 53 is slidably mounted in the hole 52 and upwardly through the recess 51, having its upper end provided with a head 54 for engaging the upper end of a spring 55 carried in the recess 51.

Rotatably supported in the vertical flanges of

the members 11 is a shaft 56 having at each end a cam 57 designed to engage corresponding heads 54 in such a manner that if the shaft 56 were rocked, the shaft 53 will be lowered until its lower end engages the floor, after which further rotation of the shaft 56 and the cams 57 will lift the corresponding ends of the members 11 and, in turn, lift the casters 47 from the floor, so that the entire weight of the corresponding end of the stand will rest on the members 53, thus providing means whereby the stand will be fixed against easy movement on the floor. Inasmuch as the rollers 45 are not swivelly mounted, the corresponding end of the stand will also be fixed against lateral movement, while the members 53 will support the stand against longitudinal movement.

In the drawing I have described and illustrated one means for elevating and lowering the corresponding end of the table 16. It will readily be seen that various devices may be devised for tilting said table about a horizontal axis without departing from the spirit of my invention.

Thus it will be seen I have provided a stand upon which an airplane engine or numerous other types of engines or devices may be mounted for repair, and when so mounted the engine or device may be supported to rotate freely about a vertical axis, or, if so desired, may be swung to position where it may be rotated freely about a horizontal axis, and in connection therewith means for easily and quickly locking the device and the tiltable supporting elements in their various adjusted positions; and, further in connection with a stand of the type above described, means whereby the stand may be easily moved from one position to another over the floor or whereby it may be easily and quickly locked against free movement.

I claim as my invention:

1. An engine stand comprising a supporting frame, a table pivoted to the upper end of said frame to swing about a horizontal axis, an annular engine base, a series of grooved rollers carried by said table for receiving and supporting the periphery of said engine base to permit said base to rotate about an axis perpendicular to said table, means for locking said annular base against rotation, and means for tilting said table.

2. An engine stand comprising a supporting frame, a table pivoted to the upper end of said frame to swing about a horizontal axis, an annular engine base having a series of holes for receiving bolts by means of which an engine may be secured to said base, a series of grooved rollers carried by said table for receiving and supporting the periphery of said engine base to permit said base to rotate about an axis perpendicular to said table, means for locking said annular base against rotation, and means for tilting said table.

LOUIS CLERGY.
